UNITED STATES PATENT OFFICE.

WALTER BROWN, OF RACINE, WISCONSIN, ASSIGNOR TO WEBSTER ELECTRIC COMPANY,
OF RACINE, WISCONSIN, A CORPORATION OF WEST VIRGINIA.

PRIMING DEVICE FOR INTERNAL-COMBUSTION ENGINES.

1,231,124.

Specification of Letters Patent. Patented June 26, 1917.

Application filed March 8, 1916. Serial No. 82,805.

To all whom it may concern:

Be it known that I, WALTER BROWN, a citizen of the United States, residing at Racine, in the county of Racine and State 5 of Wisconsin, have invented certain new and useful Improvements in Priming Devices for Internal-Combustion Engines, (Case 2,) of which the following is a full, clear, concise, and exact description, reference being had to the accompanying drawings, forming a part of this specification.

My invention relates to priming devices for internal combustion engines and has for its object the provision of a primer attached 15 to or forming part of a make and break contact support which is sturdy in construction, which can be easily and quickly operated, and which can be cheaply manufactured.

20 In a make and break contact ignition system for internal combustion engines it is the practice to mount the electrodes upon a support or bracket and often times to also mount a magneto on the bracket for furnishing the electrical energy for the ignition system. In the preferred form of my invention I provide this bracket with a well to receive the priming agent, the lower end 25 of the well communicating through a bore in the bracket with the combustion chamber of the engine. To control communication between the well and the combustion chamber I provide novel valve mechanism which can be cheaply manufactured and which 30 can be quickly opened or closed, the closing of the valve in the preferred form of my invention being done automatically by spring means.

My invention will be more clearly understood by referring to the accompanying drawings, in which—

Figure 1 is a side elevational view of the make and break contact bracket showing a magneto mounted thereon and provided 45 with the priming attachment of my invention, some of the parts being broken away to more clearly illustrate the interior construction.

Fig. 2 is a side view of the plug and valve member for controlling communication between the well and the combustion chamber.

Fig. 3 is a slightly modified form of valve member which dispenses with the spring for nor-

mally holding the valve member in closed position.

Fig. 4 is a side elevational view of the plug and valve member illustrated in Fig. 3, the valve member in this figure being shown in open position.

Fig. 5 is a fragmentary view similar to Fig. 1, illustrating a modified form of primer attachment wherein the well is contained by the plug instead of by the contact bracket, and

Fig. 6 is a side elevational view of the plug illustrated in Fig. 5.

Similar characters of reference refer to similar parts throughout the several views.

It is not thought necessary to go into the detailed description of the make and break contacts or the magneto since the details of these features form no part of my invention and will therefore refer to them briefly.

The internal combustion engine wall is illustrated in dotted lines at 8, through which extends the plug 9 supporting the make and break contacts 10. The contacts 10 are thus located within the combustion chamber and furnish the sparks necessary to ignite the compressed gases. The plug 9 forms part of the support or bracket 11 which is bolted or otherwise secured to the casing of the engine. The support 11 may extend outwardly as illustrated to support the magneto 12. The magneto contains a rotor shaft upon which is mounted the trip finger 13 operated by the internal combustion engine at the desired point of the engine cycle. This trip finger may be arranged to operate the movable electrode 10 by means of the connecting arm 14, but it will readily be understood that so far as my invention is concerned other means may be employed for operating the electrodes or the magneto.

The bracket 11 contains at its upper end a well 15 arranged to receive the priming agent or the gasoline for priming purposes. The lower end of this well communicates by means of the bore 16 with the combustion chamber, as illustrated. The communication between the well and the bore 16 is controlled by means of a valve in the form of a plug 17 screwed into or otherwise secured to the support, and preferably extending ver-

tically through the center of the well. The plug 17 is provided with a bore 18, which affords communication between the well and the bore 16. For closing the lower end of the bore 18 I provide the plunger valve member 19, which contains at its lower end the enlarged portion 20 and at its upper end the finger piece 21. A spring 22 is interposed between the finger piece and the plug to normally hold the valve member in closed position. In priming the engine gasoline is poured into the well 15 and the finger piece 21 depressed to permit the gasoline to travel downwardly into the combustion chamber. Immediately upon releasing the finger piece the valve is caused to close and thus prevent communication between the combustion chamber and the atmosphere.

20 In the modification illustrated in Figs. 3 and 4, the spring 22 is dispensed with and a cam lever 23 employed. This lever is bifurcated and pivoted at 24 to the plunger valve member 19^a and has formed thereon the cams 25—25 arranged eccentric with the pivot 24. When the lever 23 is in the position illustrated in Fig. 3, the valve member 19^a is drawn upwardly and communication between the well and the combustion chamber 25 prevented. When, however, the lever 23 is pulled upwardly to the position illustrated in Fig. 4, the valve member 19^a is lowered and assumes the position illustrated to permit gasoline to flow from the well to the combustion chamber. In the modification illustrated in Figs. 5 and 6 the plug 17^b instead of the support contains the well. The plunger valve member 19^b carries the finger piece 21^b, between which and the base of the well the spring 22^b is positioned to normally hold the valve in closed position. The bore 18^b in the plug communicates with the well through the smaller bores 26, converging downwardly from the well. The plugs 17, 17^a and 17^b are preferably made hexagonal in shape to facilitate the ready attachment and detachment thereof.

45 Having thus described my invention what

I claim as new and desire to secure by Letters Patent of the United States, is:

1. A primer for internal combustion engines comprising a make and break contact support provided with a well to receive the priming agent, a plug extending vertically through the center of the well and secured to the support, said plug being provided, with a bore extending between the lower end of the plug and the lower end of the well, a plunger valve member extending longitudinally through the plug for closing the lower end of the bore, a finger piece carried at the upper end of the member, and a spring interposed between the finger piece and plug to normally hold the valve in closed position, the lower end of the bore communicating with the combustion chamber of the engine whereby the priming agent is caused to empty into the combustion chamber when the valve member is depressed.

2. A primer for internal combustion engines comprising a plug having a bore extending vertically therethrough and having its lower end externally threaded to thread into an internally threaded part carried by the engine, the internally threaded part having communication with the combustion chamber of the engine, a plunger valve member extending vertically through the bore and having an enlarged lower end to seal the bore when said end is held in engagement with the plug, the upper end of said plunger valve extending beyond the plug and being there provided with means for normally holding the valve member in closed position, whereby a priming agent may be fed through the bore to the combustion chamber of the engine when the plunger valve member is moved downwardly to provide communication between the bore and the combustion chamber.

In witness whereof I hereunto subscribe my name this 6th day of March, A. D. 1916.

WALTER BROWN.
